STRAP SEALING TOOL

James M. Thornberry, Morton Grove, and Richard N. Modjeski, Chicago, Ill., assignors to Acme Steel Company, Chicago, Ill., a corporation of Illinois

Application February 16, 1955, Serial No. 483,546

11 Claims. (Cl. 81—9.1)

This invention relates to strap sealing tools adapted for use in forming joints between the overlapping ends of metal straps employed in binding boxes or packages and in securing together a plurality of boxes or packages in the loading of freight cars and other carriers. The overlapping ends of these binding straps are commonly secured together by the use of surrounding metal seals and sealing tools are employed to deform the seals and the enclosed strap ends and thereby form interlocking joints. One difficulty which has been encountered in the use of tools of this type is that the operator sometimes fails to operate them to the full extent so that incomplete or defective joints are formed.

The principal object of the present invention is to provide an improved strap sealing tool comprising means for insuring the completion of an interlocking joint between the seal and the strap ends each time that the operation of the tool is initiated. A further object of the invention is to provide a strap sealing tool comprising relatively movable lever arms adapted to operate mechanism for deforming a seal and enclosed strap ends, in combination with means for preventing a reverse relative movement of these lever arms until a complete joint has been formed when their relative movement to form a joint has once been started. Other objects relate to various features of construction and arrangement which will appear more clearly hereinafter.

The nature of the invention will be understood from the following specification taken with the accompanying drawings in which one embodiment is illustrated. In the drawings,

Figure 1 shows the side elevation of a strap sealing tool embodying the present invention;

Fig. 2 shows a vertical section taken on the line 2—2 of Fig. 1;

Fig. 3 shows a perspective view of a type of strap joint which may be formed with the use of the present invention;

Fig. 4 shows a side elevation similar to that of Fig. 1 with parts broken away to illustrate the relative positions of other parts when the jaws are closed to form a strap joint;

Fig. 5 shows a view similar to that of Fig. 4 with one side plate of the tool removed, illustrating the relative positions of the parts when the jaws of the tool have been opened;

Fig. 6 shows a top plan view of the tool illustrated in Fig. 1;

Fig. 7 shows a horizontal section taken along the line 7—7 of Fig. 1 showing the relative positions of the parts of the locking mechanism at the beginning of the operation of the tool;

Fig. 8 is a sectional view similar to that of Fig. 7 showing the relative positions of the parts of the locking mechanism after the jaws have been partially separated to receive a seal and the enclosed strap ends;

Fig. 9 is a sectional view similar to that of Fig. 7 showing the relative positions of the parts at a still later stage of the operation; and

Fig. 10 is a sectional view similar to those of Figs. 7, 8 and 9 showing the relative positions of the parts of the locking mechanism at a still later stage of the operation.

2

The type of joint which may be formed by the use of the sealing tool of the present invention is illustrated in Fig. 3 where a metal strap 15 is shown having its ends 15a and 15b overlapping and enclosed by a tubular metal seal 16. The edges of the seal and the enclosed strap ends have been deformed as shown at 17 in order to cause parts of the seal and the strap to abut against each other and thereby provide an interlocking joint. The features of the present invention have been illustrated in connection with the type of sealing tool which is described and claimed in the copending application of James M. Thornberry and James N. Wognum, Serial No. 480,244, filed January 6, 1955, but the present improvements may be embodied in other types of sealing tools in order to insure the formation of a complete joint each time that the operation of the tool is initiated. As illustrated in the accompanying drawings, the invention is embodied in a sealing tool comprising two side plates 18 and 19 which are generally triangular in shape and which are provided with extensions 18a and 19a having secured between them a metal block 20 provided with a cylindrical aperture in which a tubular lever or handle 21 is secured by means of a transverse bolt 22 and a nut 23.

The two side plates 18 and 19 are secured together and spaced apart by a block 24 which is fixed in position between the side plates by means of bolts 25 having nuts 26 secured on their threaded extremities. The bolts 25 and nuts 26 also serve to secure in place in contact with the side plate 18 a locking plate 27 which is substantially triangular in shape with flat faces 27a, 27b and 27c at its corners.

The side plates 18 and 19 have pivotally mounted between them two pairs of bending jaws or dies 28 which are mounted to pivot on the pins 29 having threaded extremities which are engaged by the nuts 30. These pins 29 have heads 29a provided with flat faces 29b adapted to coat with the flat corner portions 27a and 27b of the locking plate 27 so that the pins 29 are thereby held against rotation. The bending dies 28 have hooked projections 28a which are adapted to be extended beneath the seal and the enclosed strap ends when they are moved toward each other after placing the seal and strap ends between them as illustrated in Fig. 5 and the two jaws 28 of each pair are located on opposite sides of a deforming die 32, each of which is rotatably mounted upon one of the pins 29. The dies 32 are circular in form and are provided with outer annular surfaces which are transversely curved so that when the bending dies 28 are closed upon each other from the positions shown in Fig. 5 to the positions shown in Fig. 4, the extremities 28a of the bending jaws project the seal and the enclosed strap ends upwardly and against the peripheral surfaces of the deforming dies 32 with the result that the lateral edges of the seal and the corresponding portions of the overlapping strap ends are deformed as shown at 17 in Fig. 3. During this operation, the seal and the enclosed strap ends are projected upwardly against the block 24 which serves as a saddle to support the seal during the deforming operation and which supplements the action of the edges 18c and 19c of the side plates which are notched upwardly on opposite sides in order to form recesses through which the strap ends and the seal are adapted to extend.

The bending dies or jaws 28 have upwardly extending arms 28b which serve as levers by which the dies are rocked about the pivot pins 29. The mechanism for operating the lever arms 28b comprises an operating lever or handle 35 which lies parallel to the handle 21 when the jaws are closed as shown in Fig. 1. The lever or handle 35 fits into a tubular bore formed in a yoke-shaped bracket 36 where it is secured by a transverse pin 37. The yoke 36 has two transversely extending flanges

36a and 36b which extend between the side plates 18 and 19 and which are provided with apertures which are pivotally engaged by a pin 38 having a threaded extremity which is engaged by a nut 39. The pin 38 has a head 38a provided with a flat face 38b adapted to seat against the flat corner portion 27c of the locking plate 27 so that the pin is thereby held against rotation.

The side flanges 36a and 36b of the yoke 36 are pivotally connected by a pin 40 to a link 41 which has its other extremity extending between two of the bending jaw arms 28b with which it is pivotally connected by a pin 42. At a point on the opposite side of the pin 38 from the pin 40, the flanges 36a and 36b of the yoke are pivotally connected by a hollow shaft 44 to a link 45 which has its outer extremity pivotally connected with the arms 28b of the other bending jaws by means of a pin 46. The pin 40 and the hollow shaft 44 are located between the side plates 18 and 19 and are adapted to move bodily between these plates when the tool is operated as hereinafter described.

In the use of the apparatus described above the handles or levers 21 and 35 are first separated by moving the handle 35 upwardly to the position shown in Fig. 5, thereby separating the jaws 28 so that they may be caused to straddle the seal 16 and the enclosed strap ends 15a and 15b. Having placed the tool in this operating position, the handle or lever 35 is then moved downwardly to the position shown in Fig. 4 which causes the jaws 28 to close upon each other and to press the seal and the enclosed strap ends against the deforming dies 32, thereby deforming the edges of these parts as shown at 17 in Fig. 3 to provide an interlocking connection between the seal and the strap ends. The present invention is directed to improved means by which the completion of the relative movement of the levers 21 and 35, from the positions shown in Fig. 5 to the positions shown in Fig. 4, is insured so that the deformations 17 are completely formed.

The means for insuring a complete operation of the sealing tool to form an interlocking joint, when the operation of the tool has once been initiated, comprises a locking pin 50 which has a head 50a slidably mounted in the bore of the hollow shaft 44. This hollow shaft extends completely through the flanges 36a and 36b of the yoke 36 and is provided at one end with an annular flange 44a seated in a recess in the flange 36b. The other end of the hollow shaft 44 lies flush with the outer face of the flange 36a and this end of the tubular bore of the hollow shaft is provided with an inwardly extending flange 44b. A coil spring 51 is mounted within the hollow shaft 44 between the head 50a of the pin and the flange 44b of the hollow shaft and this spring is under compression so that it normally tends to move the pin 50 away from the side plate 18 as viewed in Fig. 7.

When the operating levers 31 and 35 are in the relative positions shown in Fig. 4, the locking pin 50 is held in the retracted position shown in Fig. 7 by means of a latch member 52 which is pivotally mounted upon the pin 38 and which is provided with a relatively thin arcuate blade 52a adapted to engage an annular groove 50b formed in the pin 50 between the body portion of the pin and a projecting head 50c which is of smaller diameter than the head 50a and located on the opposite end of the pin. The latch 52 is normally moved to the pin engaging position shown in Figs. 4 and 7 by means of a spring 53 which surrounds the pin 38 and has one extremity 53a coiled about the pin 40 while the other extremity 53b thereof bears upon a flat surface 52b of the latch so that the latch is normally urged in a counterclockwise direction as viewed in Fig. 5.

Assuming that the operating levers 21 and 35 are in the relative positions shown in Figs. 1 and 4, the locking pin 50 is then in the position shown in Fig. 7 with the head 50c thereof extending into an arcuate recess 18d which is formed in the inner face of the side plate 18.

This recess permits the necessary movement of the locking pin 50 as the levers 21 and 35 are separated but, at a predetermined movement in this relative separation, a pin 55 secured in the latch 52 engages another pin 56 which is secured to the side plate 18 adjacent one end of the recess 18d. In Fig. 8 the latch 52 is still in the position shown in Fig. 7 when the lever 35 is at an intermediate stage of its separation from the lever 21 but, upon further movement of the lever 35, the pin 55 engages the pin 56 with the result that the latch 52 is disengaged from the groove 50b of the locking pin, against the action of the spring 51, thus releasing the pin 50 so that the spring 51 moves it to the position shown in Fig. 9.

When in the position shown in Fig. 9, the head 50a of the locking pin extends into another arcuate recess 19d which is formed in the inner face of the side plate 19. At this time, the jaws 28 are separated so that they may be caused to embrace the seal and the enclosed strap ends which are to be deformed and the lever 35 is then moved toward the lever 21 with the result that the head 50a of the locking pin rides upon the flat surface of the recess 19d until the pin snaps over a shoulder 19e which is formed in this recess, whereupon the pin 50 is projected outwardly to a further extent and is then adapted to ride upon the curved surface 19f of the arcuate recess in the inner face of the side plate 19. As the pin 50 snaps over the shoulder 19e the deformation 17 in the seal and strap ends are partially formed and it is then impossible to reverse the relative movement of the lever arms 21 and 35 to separate the jaws because of the engagement of the shoulder 19e with the pin 50. Thus, the only way to release the tool from the seal and the strap ends is to continue the relative movement of the lever 35 toward the lever 21 with the result that the head 50a of the locking pin rides on the curved cam surface 19f of the side plate 19 until a point is reached where the jaws have been fully closed as shown in Fig. 1 and the pin 50 has been pushed inwardly by the cam surface 19f until it again occupies the position shown in Fig. 7, whereupon the latch 52 is actuated by the spring 53 to engage the groove 50b in the locking pin and hold it in its retracted position in readiness for a new joint forming operation. In this way, successive complete joint forming operations are insured and, at the end of one operation, the parts of the tool are in readiness for the next succeeding operation.

Although one form of the invention has been shown and described by way of illustration, it will be understood that it may be constructed in various other embodiments which come within the scope of the appended claims.

We claim:

1. The combination in a tool adapted to form a joint between a metal seal and enclosed overlapping metal strap ends, of a pair of side plates secured together and spaced apart, a pair of relatively movable jaws mounted between said plates and each comprising a deforming die, actuating means mounted for movement parallel to said plates for actuating said jaws to cause said dies to deform the seal and said strap ends, and means carried by said actuating means and located between and coacting with said plates for insuring a complete joint forming movement of said actuating means when such movement is once initiated.
2. The combination in a tool adapted to form a joint between a metal seal and enclosed overlapping metal strap ends, of a pair of side plates secured together and spaced apart, a pair of relatively movable jaws mounted between said plates and each comprising a deforming die, means comprising parts movable between said plates for actuating said jaws to deform said seal and said enclosed strap ends, and means carried by said parts and engageable with said side plates for regulating the amplitude of relative movement of said jaws.

3. The combination in a tool adapted to form a joint between a metal seal and enclosed overlapping metal strap ends, of a pair of side plates secured together and spaced apart, means comprising relatively movable parts mounted between said side plates for deforming said seal and said strap ends, means for actuating said last named means, and a controlling member movable with said actuating means for controlling the movement of said jaws, said side plates having parts adapted to engage said controlling member to regulate the action thereof.

4. The combination in a tool adapted to form a joint between a metal seal and enclosed overlapping metal strap ends, of a pair of side plates secured together and spaced apart, means comprising relatively movable parts mounted between said side plates for deforming said seal and said strap ends, means for actuating said last named means, and a controlling member mounted for movement with said movable parts movable transversely of said side plates for controlling the movement of said jaws, said side plates having parts adapted to regulate the action of said controlling member.

5. The combination in a tool adapted to form a joint between a metal seal and enclosed metal strap ends, of relatively movable parts adapted to deform said seal and said strap ends to form an interlocking joint, means for actuating said parts through forward and reverse relative movements, a locking pin movable with said last named means, and means mounted in the path of said pin for engaging said pin during the relative movement of said parts for moving said pin endwise and controlling the relative movement of said parts.

6. The combination in a tool adapted to form a joint between a metal seal and enclosed metal strap ends, of relatively movable parts adapted to deform said seal and said strap ends to form an interlocking joint, means for actuating said parts through forward and reverse relative movements, a locking pin movable with said last named means, means movable with said parts for latching said pin in a retracted position, means comprising a part located in the path of movement of a part of said latching means and actuated during the reverse relative movement of said parts for releasing said pin, means movable with said pin for then moving said pin endwise to a second position, and means located in position to engage said pin and operative after said parts have started forward relative movements for preventing reverse relative movement of said parts by engagement with said pin.

7. The combination in a tool adapted to form a joint between a metal seal and enclosed metal strap ends, of relatively movable parts adapted to deform said seal and said strap ends to form an interlocking joint, means for actuating said parts through forward and reverse relative movements, a locking pin movable with said last named means, means movable with said parts for latching said pin in a retracted position, means comprising a part located in the path of movement of a part of said latching means and actuated during the reverse relative movement of said parts for releasing said pin, means movable with said pin for then moving said pin endwise to a second position, said last named means being operative after said parts have started forward relative movements for causing said last named means to move said pin to a third position, and located in the path of reverse movement of said pin and operative when said pin is in said third position for preventing reverse relative movements of said parts.

8. The combination in a tool adapted to form a joint between a metal seal and enclosed metal strap ends, of relatively movable parts adapted to deform said seal and said strap ends to form an interlocking joint, means for actuating said parts through forward and reverse relative movements, a locking pin movable with said last named means, means movable with said parts for latching said pin in a retracted position, means comprising a part located in the path of movement of a part of said latching means and actuated during the reverse relative movement

of said parts for releasing said pin, means movable with said pin for then moving said pin endwise to a second position, means engageable with said pin and operative after said parts have started forward relative movements for causing said last named means to move said pin to a third position, means located in the path of reverse movement of said pin and operative when said pin is in said third position for preventing reverse relative movements of said parts, and means located in the path of movement of said pin and operative as said parts complete their forward relative movements for restoring said pin to its original position.

9. The combination in a tool adapted to form a joint between a metal seal and enclosed overlapping strap ends, of a pair of side plates secured together and spaced apart, means comprising parts having relative movement between said side plates for deforming said seal and said strap ends, said parts being movable through forward and reverse strokes, a locking pin mounted on said parts for angular movement bodily between said side plates during said relative movements of said parts and also for end-wise movement transversely to said side plates, means movable with said pin for normally holding said pin in a retracted position, and means on one of said plates for actuating said holding means to release said pin during the movement of said parts through said reverse stroke.

10. The combination in a tool adapted to form a joint between a metal seal and enclosed overlapping strap ends, of a pair of side plates secured together and spaced apart, 30 means comprising parts having relative movement between said side plates for deforming said seal and said strap ends, said parts being movable through forward and reverse strokes, a locking pin mounted on said parts for angular movement bodily between said side plates during 35 said relative movements of said parts and also for endwise movement transversely to said side plates, means movable with said pin for normally holding said pin in a retracted position, means in the path of said holding means operative during the relative movement of said 40 parts during said reverse stroke for actuating said holding means to release said pin, resilient means tending to move said pin endwise from said retracted position, means carried by one of said side plates for releasing said pin from said holding means during said reverse stroke, and means 45 carried by the other side plate for causing further endwise movement of said pin during the forward stroke and for then preventing a reverse stroke.

11. The combination in a tool adapted to form a joint between a metal seal and enclosed overlapping strap ends, of a pair of side plates secured together and spaced apart, means comprising parts having relative movement between said side plates for deforming said seal and said strap ends, said parts being movable through forward and reverse strokes, a locking pin mounted on one of said parts for angular movement bodily between said side plates during said relative movements of said parts and also for endwise movement, means movable with said parts and engaging said pin for normally holding said pin in a retracted position, resilient means movable with said pin and tending to move said pin endwise from said retracted position, means carried by one of said side plates for releasing said pin from said holding means during said reverse stroke, means carried by the other side plate for causing further endwise movement of said pin by said resilient means during the forward stroke and for then preventing a reverse stroke, and means carried by said last named side plate and operative as said parts reach the end of said forward stroke for restoring said pin to its original position.
